UNIVERSAL FOOT SUPPORT

Halworth E. Stark, Chicago, Ill., assignor to Dr. Wood's Foot Appliance Co., Chicago, Ill., a corporation of Ohio

Application September 3, 1938, Serial No. 228,309

1 Claim. (Cl. 36—71)

This invention relates to a universal foot support, and more particularly to the type of foot support which is readily insertable in a shoe or other article of footwear beneath or over the afflicted or painful part of the foot, although the invention may have other uses and purposes as will be apparent to one skilled in the art.

I am aware that in the past many and various foot supporting devices have been developed, but in all instances of which I am aware each of these formerly known devices has been developed to perform a specific corrective function in relation to the foot and had to be disposed beneath a particular part of the foot or the device would not perform its specific function. In other words, each device had only one function and, of necessity, could occupy only one location in an article of footwear or it would not perform the particular corrective operation for which it was designed but might cause further injury to the foot of the user.

In some instances, combination supports were designed in that a single support was made to provide pressure beneath the inner longitudinal arch and also provide pressure beneath the anterior or metatarsal arch. However, the device had only one position within a shoe and would aid only the particular affliction or afflictions for which it was especially designed. Further, many of these formerly known supporting devices were also designed for permanent positioning within a shoe or other article of footwear. They could not feasibly be transferred from one shoe to another, and in the event a user overcame a weak metatarsal arch with the aid of the appliance and then suffered from a painful heel, a new appliance had to be purchased for the correction of the latter affliction.

With the foregoing in mind, it is an important object of the present invention to provide what may be termed a universal foot support or appliance, in that the support may be positioned in substantially any desirable location within a shoe, depending upon what part of the foot is afflicted.

Another object of the invention is the provision of a universal foot support or appliance embodying a unitary device which may be positioned in a desired location in a shoe and which in and of itself will provide aid and relief for various foot ailments, such as flat foot, painful heel, outer arch weakness, cuboid trouble, metatarsalgia, bunions, heel blisters, etc.

A further object of the invention is the provision of a foot supporting device positionable in

substantially any desirable location within a shoe, and which is constructed so that it stays in place without any additional securing means and may be readily changed from one shoe to another.

It is also an object of the invention to provide a foot supporting device which is substantially self-adjusting and self-conformable to the shoe and the foot of a user, so that it exerts gentle pressure upon the foot where such pressure is needed.

Still another object of the invention is the provision of a resilient foot support or appliance which may be placed under, around or on top of the foot at any point where the device feels most comfortable to the user.

Still a further feature of the invention is the provision of a foot support having substantially the shape of a disk with a flat undersurface, a convex upper surface, and which is of such size as to buckle in a portion thereof when placed in most positions within a shoe, to aid in insuring that the device will remain in a desired location within the shoe.

A still further object of this invention is to provide an appliance which may function as a support or a pressure relieving member, as desired, and which may be positioned substantially where desired in a shoe, and changed from one position to another or from one shoe to another, as needed.

While some of the more salient features, characteristics and advantages of the present invention have been above pointed out, others will become apparent from the following disclosures, taken in conjunction with the accompanying drawing, in which:

Figure 1 is a diagrammatic view indicating various dispositions of a support embodying principles of the present invention in a shoe or similar article of footwear;

Figure 2 is a plan view of a preferred form of the device itself;

Figure 3 is a central vertical sectional view of the device of Figure 2;

Figure 4 is a vertical sectional view of a shoe with the device positioned therein, the shoe being illustrated somewhat diagrammatically; and

Figure 5 is also a sectional view of a shoe, with a foot shown diagrammatically and illustrating the device in a different position to perform a different function.

As shown on the drawing:

The illustrated embodiment of the present invention, with reference to Figures 2 and 3, comprises a pad 5 of substantially circular shape and

made of sponge rubber or equivalent resilient material. The pad 5 preferably has a substantially flat undersurface 6 and a convex upper surface. The thickest portion of the pad is preferably in the central region thereof, and the pad tapers to a relatively thin edge 7.

Over the pad 5, a smooth cover 8 of any suitable material, such as flexible kidskin, is disposed so that the cover extends beyond the periphery 10 or circumference of the pad a short distance, as indicated at 9. The cover may be secured to the pad in any suitable manner, such as by cementing. Both the pad and cover are preferably of the same general peripheral shape, and the thin edge 7 coupled with the projection of the cover as at 9 insures a smooth, tight contact with the inside of the shoe.

The support is preferably made in two sizes only, small for ladies' shoes and large for men's 20 shoes, although it will be apparent that youthful and in-between sizes may be incorporated, if so desired. The preferable size of the pad is such that its diameter will more than span the major portion of the insole of the shoe, especially at the 25 shank of the shoe. Consequently, when placed in a shoe as illustrated in Figure 4, the pad is somewhat deformed or buckled and is therefore much less likely to shift positions, even though the shoe may be repeatedly placed upon and re- 30 moved from the foot.

In Figure 4, a diagrammatic indication of a shoe is illustrated including the usual upper 10, the customary insole 11 and the outsole 12. In this instance, the support has been placed substantially evenly in the forward part of the shank portion of the shoe, so that both sides of the support are buckled against the shoe upper, as indicated at 13-13. The gripping of quasi-adhesive action of the rubber undersurface is materially enhanced by this buckling, and the pad remains firmly in its selected position within the shoe. At the same time, the pad may be readily removed from the shoe with little effort and be placed in another shoe or in the same shoe in 45 a different location.

The universal character or versatility of the present invention is indicated to a partial degree in Figure 1. The insole 11 of the shoe is diagrammatically illustrated and certain locations 50 of the support indicated. For example, the full line position 14 corresponds with the showing in Figure 4. The dotted line portions 13a-13a of the position 14 indicate approximately the part that is buckled, indicated at 13-13 in Figure 4.

When placed in this position, the resilient support is beneficial to various foot ailments or afflictions, such as painful great toe, trouble at the ball of the foot, callouses, metatarsalgia, etc.

When the device is placed in the dotted line 60 position 15, it will be beneficial to a fallen or weak inner longitudinal arch and also relieve painful heel and other disorders occurrent in this region of the foot. In this position, it will be noted that only one side of the support will buckle 65 when placed in the shank portion of the shoe, thereby causing the support to materially aid the inner longitudinal arch of the foot.

When the device is placed in the position 16,

also shown in dotted lines, it is effective for the relief of such ailments as outer longitudinal arch weakness, painful heel, cuboid trouble, etc.

To further indicate the universal character of the device, in Figure 5 I have illustrated the appliance in position within a shoe to relieve shoe pressure on a bunion near the metatarsal head of the great toe, generally indicated by numeral 17. The shoe is the same as previously described, and it is simply necessary to curl the device around the inner side wall part of the shoe 10 rearwardly of the first metatarsal joint, the major part of the appliance being in contact with the shoe upper.

It will therefore be appreciated that the device 15 may be positioned in various other locations, such, for example, as behind a tailor's bunion, directly beneath the os calcis, over the top of the instep as a tongue pad, substantially vertically against the counter of a shoe to relieve or prevent heel blisters, etc.

In short, the device may be placed in any position 20 within a shoe where it will be of most benefit to the wearer. While it is appreciated that the substantially circular contour of the device 25 facilitates its ready positioning and also facilitates the gripping action of the device against the shoe so that it will stay in position, the size of the device also maintains it in position and causes the device to be automatically self-adjusting and self-conforming both to the foot and the shoe. On the other hand, it will be appreciated that the nearly exact circular shape is not an absolute essential, but this shape may be varied somewhat without departing from the 30 principles of the invention.

From the foregoing, it is apparent that I have provided a novel foot support or appliance of simple and economical construction, which is substantially universal in its use in that it may 40 be positioned in substantially any desirable point within an article of footwear, and by exerting a gentle resilient pressure where needed against the human foot, the device is capable of relieving or correcting most of the common ailments of 45 the human foot.

I am aware that many changes may be made and numerous details of construction may be varied through a wide range without departing from the principles of this invention, and I, therefore, do not purpose limiting the patent granted hereon otherwise than is necessitated by the prior art.

I claim as my invention:

A foot-correcting pad adapted to be variously 55 positioned in a shoe and also adapted to be reversely bent as a toe cushion in the shoe, said pad consisting of a circular piece of sponge rubber having a flat under surface for gripping contact with the insole and upper of a shoe, said 60 pad having a cross section such that it defines a convex central section tapering to a thin peripheral section, and having a diameter greater than the width of the insole with which it is to be used. the upper surface of said pad being 65 covered with a soft leather cover which extends evenly beyond the peripheral edge of the pad.

HALWORTH E. STARK.
